RAILWAY DRAFT RIGGING

Original Filed March 10, 1928

UNITED STATES PATENT OFFICE

ERNEST R. SCHULZ, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed March 10, 1928, Serial No. 260,741. Renewed August 23, 1930.

This invention relates to improvements in railway draft riggings.

In railway practice, especially in the operation of freight cars, a frequent source of trouble has been the inability to maintain the standard coupler in proper horizontal condition to align truly with the shock absorbing mechanism. This is due principally to the coupler shank being keyed to the yoke or links at a point inwardly of the buffer block, and the main support for the coupler being the usual carry iron located at a point outwardly of the key connection. The coupler head being relatively heavy and the carry iron relatively narrow, there is thus a tendency for the coupler head to droop by rocking on the carry iron, thereby disturbing the true horizontal alignment of the coupler shank with the shock absorbing mechanism. The overbalanced condition of the coupler has a constant tendency to destroy the carry iron.

The difficulties pointed out obviously become greater when the coupler travel is increased. Inasmuch as there is at the present time a definite tendency, in railway practice, to increase the coupler travel over the approximate two and three-quarters inches usually employed, and particularly in buff, the overhang of the coupler head in the normal full release condition and in full draft of the parts is materially increased, with resultant damaging effect.

One object of my invention is to provide simple, efficient, and inexpensive means for overcoming the defects pointed out, by properly supporting the coupler so as to assure true alignment of the shank thereof with the shock absorbing mechanism at all times.

Another object of the invention is to provide means for associating the coupler and draft acting means of a railway draft rigging, whereby the coupler shank is adequately supported and maintained in proper alignment with the shock absorbing mechanism, the improved means being particularly adapted for use in draft riggings employing a yoke acting member enclosing the shock absorbing mechanism proper.

More specifically, an object of my inven-

tion is to provide, in a railway draft rigging including the usual yoke enclosing the shock absorbing mechanism, supporting means for the coupler shank of a railway draft rigging which is so arranged as to sustain the weight of the major portion of the coupler shank, and is in turn supported by both the usual carry iron and the yoke member, whereby the coupler is maintained in proper alignment with the shock absorbing mechanism.

A still further object of the invention is to provide means for supporting the coupler of a railway draft rigging in proper alignment with the shock absorbing mechanism and maintaining such alignment, including a supporting wear plate for the coupler shank having sliding engagement with the carry iron and supported at the rear end directly by the yoke member with which it interlocks, the supporting wear plate extending outwardly closely adjacent the coupler head, thereby preventing rocking of the same.

Another and more specific object of the invention is to provide, in a railway draft rigging including the usual coupler co-operating with a shock absorbing mechanism, a wear plate supported and guided by the usual carry iron and in turn supporting the coupler shank, together with a yoke member enclosing the shock absorbing means, the yoke member being provided with the usual coupler shank receiving hood section, the rear end of the wear plate being supported on the bottom wall of the hood section and the extended side walls of the hood bearing on opposite sides of the wear plate to maintain the same aligned with the yoke, the wear plate and yoke thus, in effect, forming a unitary structure, whereby the weight of the coupler head,

the shank of which is keyed to the yoke, is overbalanced by the weight of the yoke and enclosed shock absorbing mechanism, thereby preventing rocking of the coupler and drooping of the head thereof and assuring continued alignment of the coupler shank and shock absorbing mechanism.

Other and further objects of my invention will more clearly appear from the description and claims hereinafter following.

In the drawing, forming a part of this

specification, Figure 1 is a longitudinal sectional view of a portion of a railway car at one end thereof, showing my improvements in connection therewith. Figure 2 is a horizontal, longitudinal sectional view, corresponding substantially to the line 2—2 of Figure 1. Figure 3 is a transverse, vertical sectional view, corresponding substantially to the line 3—3 of Figure 1. And Figure 4 is a plan view of a supporting wear plate employed in connection with my improved mechanism.

In said drawing, 10—10 indicate the usual center or draft sills of a railway car under-frame, having the usual front stop lugs 11—11 secured thereto. A spacing bolster filler casting 12 is secured to the draft sills and is provided with forward extensions 13—13 forming the rear stop lugs of the mechanism. The bolster filler casting 12 is associated with the usual bolster indicated by 14. The angle end sill is designated by 15 and has secured thereto the striking casting 16, which is of well known form. The coupler is designated by 17 and is of the usual type, having a connecting shank which is suitably secured to the yoke member of the shock absorbing mechanism. The shock absorbing mechanism proper is designated by 18 and is disposed within the yoke.

My improved mechanism for maintaining alignment of the coupler and shock absorbing mechanism comprises, broadly, a carry iron A; a wear plate B, guided by the carry iron; and a yoke C, interlocked with the wear plate and enclosing the shock absorbing mechanism 18.

The yoke member C is supported by front and rear saddle plates 19—19 secured to the draft sills in any suitable manner, the same being herein disclosed as secured by bolts. The yoke member C is of the hooded type and has the usual spaced top and bottom arms 20—20 connected by a rear end section 21, which is adapted to co-operate either directly with the rear end of the shock absorbing mechanism or a rear follower. In the present instance, the shock absorbing mechanism is shown as of the friction shell type, the shell member thereof bearing directly on the rear end section 21 of the yoke and co-operating with the rear stop lugs 13.

While the shock absorbing mechanism 18 herein shown is illustrated as of the friction shell type, it will be evident that it is within the invention to employ any well known shock absorbing mechanism either of the friction or spring type. The hood section of the yoke, which is designated by 22, is defined by top and bottom walls 23 and 24, and spaced vertical side walls 25—25. The top wall, as most clearly shown in Figure 1, has the forward end portion thereof downwardly inclined and extended forwardly beyond the bottom wall 24. The bottom wall 24, at the

forward end portion thereof, is thickened, as shown, thereby providing a flat raised supporting surface 126, which is adapted to co-operate with the wear plate B, as hereinafter more clearly pointed out. The side wall members 25 of the hood section of the yoke extend forwardly beyond the top wall, as most clearly shown in Figures 1 and 2. The side walls 25 preferably diverge outwardly, as shown in Figure 2.

In the present instance, the shock absorbing mechanism, which is illustrated as of the friction shell type, co-operates directly with a front main follower 26, which bears on the usual wedge member 27 co-operating with the friction shoes 28—28. The follower 26 engages directly the inner end portions of the side walls 25 and the shoulder 29 on the bottom wall of the hood section of the yoke, and also co-operates in the usual manner with the front stop lugs 11—11. The shank of the coupler 17 extends into the hood section 22 of the yoke and is so arranged that the butt end thereof co-operates with the front follower 26. The shank of the coupler 17 is connected to the yoke by means of a transverse key 30 extending through aligned openings in the coupler shank, the side walls 25 of the hood of the yoke and key receiving slots 31—31 in the draft sills 10. As shown, the key 30 substantially fits the opening in the shank of the coupler, there being only slight longitudinal play permitted between the same and the coupler, as most clearly shown in Figure 1. The openings in the side walls of the hood are so proportioned that inward movement of the coupler, with respect to the yoke, is permitted during a buffing action of the mechanism. The key receiving slots of the draft sills are of such a length that movement of the key therein is permitted during both buff and draft.

Although my improvements may be employed equally well in connection with railway draft riggings, wherein the buffing and draft strokes are equal, in the present instance the same is illustrated in connection with the construction of railway draft riggings, wherein the buffing stroke of the mechanism is considerably greater than the draft stroke. Upon reference to Figure 2, in which the parts of the mechanism are illustrated in full release position, it will be seen that the coupler key is disposed nearest the front ends of the key receiving slots 31.

The carry iron A, which is most clearly illustrated in Figures 1 and 3, is secured to the draft sills adjacent the front ends thereof and is provided with an upstanding section 32 having laterally projecting guide flanges 33—33, thereby presenting a guide member of the T-head formation.

The wear plate B is interposed between the carry iron A and the bottom of the coupler shank. As most clearly shown in Figure 4,

the wear plate B is of generally rectangular outline and has a rearwardly projecting tongue section 34 which is adapted to extend into the hood portion 22 of the yoke C. The plate B is provided with a transverse rib 35 on the bottom side thereof, adapted to act as a limiting stop co-operating with the inner edge of the carry iron A and also with the front end of the bottom wall section 24 of the hood of the yoke.

In the normal position of the parts, as shown in the drawing, the rib 35 is in abutment with the carry iron A, thus holding the plate B against outward movement. The rib 35 thus serves as a limiting stop for the yoke during a draft action, outward movement of the yoke being arrested by engagement of the front edge of the bottom wall of the hood thereof with the rib.

As clearly illustrated in Figures 3 and 4, the main body portion of the supporting wear plate B is considerably wider than the tongue section 34 thereof, and the outer edge portions of the main body portion of the plate are extended downwardly and inwardly, thereby providing guide channels 36 at opposite sides thereof, adapted to co-operate with the guide flanges 33 of the carry iron. The plate B rests directly on the top surface of the T-section of the carry iron, and the rearwardly extending tongue 34 thereof bears directly on the supporting surface 126 of the bottom wall 24 of the hood section of the yoke C. As shown in Figures 1 and 2, in the normal full release position of the parts, the front end of the supporting wear plate B extends a considerable distance beyond the carry iron A and closely adjacent the head of the coupler. The coupler horn or head has the upper section thereof preferably spaced from the front face of the buffer block casting a distance equal to the permissible buffing stroke of the mechanism, this distance being equal to the spacing between the key 30 and the rear end walls of the slots 31 in the position of the parts illustrated in Figure 2. It is further pointed out that the combined distance between the coupler head and the front end of the supporting wear plate B, and between the rib 35 and the front end of the bottom wall of the hood section of the yoke, is such as to equal the distance the coupler is permitted to move during a buffing stroke.

The wear plate B is of such a thickness that the same will fit snugly between the bottom edge portions of the side wall sections 25 of the hood of the yoke and the supporting surface 126 of the bottom wall 24 thereof, the side wall sections 25 of the hood bearing, for substantially their entire length, on the side portions of the main body portion of the plate, which side portions, as shown in Figure 4, project a considerable distance laterally beyond the corresponding sides of the tongue 34.

The operation of my improved mechanism, assuming a buffing stroke, is as follows: The coupler 17 will be forced inwardly, compressing the friction shock absorbing mechanism 18 through the medium of the front follower 26, the butt end of the coupler shank bearing directly on the follower 26 and being slidable with respect to the yoke C. During the inward movement of the coupler, the key 30 will be carried rearwardly therewith along the slots 31 of the draft sills. There will also be a tendency of the supporting wear plate B to be carried inwardly with the coupler, due to the friction existing between the coupler shank and the plate. There will, however, also, be some slippage between these parts, and the coupler head will finally engage the front end of the wear plate B and the rib 35 of the wear plate will be brought into engagement with the front end of the bottom wall of the hood section of the yoke. The condition last referred to, will exist when the mechanism has been fully compressed and the coupler key 30 has reached the limit of its inward movement, engaging the inner ends of the slots 31, and the coupler head has engaged the striking casting 16. During a draft action, the outward movement of the coupler will force the yoke to be moved outwardly therewith through the connecting key 30, thereby compressing the friction shock absorbing mechanism against the front follower 26, which is held stationary by engagement with the front stop lugs 11. The compression stroke in draft is limited by engagement of the yoke with the rib 35 of the plate B.

Inasmuch as the coupler shank is supported for substantially the entire length thereof by the wear plate B, and the wear plate B is in turn slidably supported directly by a carry iron intermediate its ends, and the rear end section thereof is interlocked with the hood portion of the yoke, and the coupler shank is keyed to the side walls of the hood of the yoke, no tilting or rocking of the coupler with respect to the yoke is possible, thereby preventing drooping of the coupler head with resultant derangement of the parts, destroying the true alignment of the coupler shank and the shock absorbing mechanism. It is further pointed out that the supporting wear plate B is interlocked with the yoke against vertical displacement, whereby the yoke and wear plate, together, in effect, form a unitary member which balances or overbalances the weight of the coupler head. To the weight of the yoke, is added the weight of the shock absorbing mechanism within the yoke, thereby increasing the balancing action of the parts. Displacement of the slidably supporting wear plate B, with respect to the carry iron A, is also prevented by means of the co-operating guide on the carry iron and supporting plate formed by the T-headed

section on the carry iron and the guide channel means on the wear plate.

While I have herein shown and described what I consider the preferred manner of carrying out my invention, the same is merely illustrative, and I contemplate all changes and modifications which come within the scope of the claims appended hereto.

I claim:

10. 1. In a draft rigging for railway cars, the combination with draft sills; of a yoke acting member between said sills; a shock absorbing mechanism within the yoke; a coupler; means for connecting the coupler shank to the yoke to effect movement of the yoke with the coupler in draft and permit relative movement of the coupler and yoke in buff; a carry iron; and means movable with respect to the yoke, interposed between the 20 carry iron and coupler shank for supporting the latter, said means extending into the yoke and locked to the yoke against vertical displacement relative thereto, whereby the weight of the coupler outwardly of the carry 25 iron is overbalanced by the weight of the yoke and shock absorbing mechanism therewithin.
2. In a draft rigging for railway cars, the combination with draft sills; of a carry iron; 30 a yoke member; a coupler; means for connecting the coupler shank to the yoke; a shock absorbing mechanism within the yoke; and a supporting member for the coupler shank movable inwardly of the yoke in buff, 35 said member being interposed between the carry iron and said shank, and having the inner end section thereof interlocked with the yoke against vertical displacement and the outer end in supporting relation to the 40 coupler shank closely adjacent the head.
3. In a railway draft rigging, the combination with draft sills; of a supporting element adjacent the outer ends of the sills; a coupler; a yoke connected to the coupler shank; a shock absorbing mechanism within the yoke; a supporting member movable with respect to the yoke, extending from the yoke between the coupler shank and the supporting element and having the outer end 45 thereof disposed adjacent the coupler head, said supporting element having the inner end thereof held against vertical displacement with respect to the yoke.
55. 4. In a railway draft rigging, the combination with spaced draft sills; of a coupler; a yoke member; a shock absorbing mechanism within the yoke member; a carry iron adjacent the outer ends of the sills; a connecting key extending through the yoke and coupler shank; a supporting wear plate interposed between the coupler shank and carry iron, said wear plate being movable on the carry iron and having the rear end thereof 60 slidably connected to the yoke and inter-

locked with the yoke against vertical displacement.

5. In a railway draft rigging, the combination with spaced draft sills; of a carry iron secured to the draft sills adjacent the outer ends thereof; a coupler; a yoke connected to the coupler shank; shock absorbing means within the yoke; and a supporting member for the coupler shank slidable on said carry iron and having a sliding connection with the yoke.

6. In a railway draft rigging, the combination with draft sills; of a hooded yoke member movable between said sills; a shock absorbing mechanism within the yoke member; a carry iron fixed to said sills; a coupler having the shank thereof connected to the hooded end of the yoke; a movable wear plate supporting the shank of the coupler and slidable on said carry iron, said plate having the inner end thereof extended into the hood section of the yoke and supported by the bottom wall of said hood section, the side walls of the hood section overhanging the sides of the plate and bearing on the top portion thereof.

7. In a railway draft rigging, the combination with spaced draft sills; of a carry iron secured to said sills; a wear plate member slidable on said carry iron, said wear plate member and carry iron having co-operating guide thereon limiting said plate member to movement in a direction lengthwise of the draft rigging; a coupler supported on said plate member; a yoke connected to the coupler shank; interengaging means on said yoke and plate member to prevent relative vertical displacement thereof; and a shock absorbing mechanism within the yoke.

8. In a railway draft rigging, the combination with draft sills; of a carry iron secured to the sills; a coupler; a yoke member having a hood section at one end, defined by top, bottom, and side walls, said hood section receiving the inner end of the coupler shank, said side walls being extended beyond the hood section proper; a key extending through the side walls and the coupler shank and holding said shank and yoke against relative vertical displacement, but permitting relative longitudinal movement of the coupler and yoke in buff; a shock absorbing mechanism within the yoke and in co-operating relation with said coupler shank; and a supporting wear plate interposed between the coupler shank and carry iron, said wear plate having the side portions thereof engaged beneath the extended side walls of the hood section of the yoke and having a tongue section extending into the yoke and supported by the bottom wall of the hood section.

9. As an article of manufacture, a combined aligning and draft member for railway draft riggings, said member comprising a

5 yoke element having a hood section at one end thereof, adapted to receive the butt end of a coupler shank, a supporting member for the coupler shank extending forwardly from the yoke to a point closely adjacent the coupler head, said member being detachably connected to the hood by sliding engagement therewith and having the attached end thereof supported against vertical displacement 10 with respect to the hood.

10. As an article of manufacture, a combined aligning and draft member for railway draft riggings, said member comprising a yoke element adapted to receive a shock absorbing mechanism; said yoke member having a hood section at one end thereof adapted to receive the butt end of a coupler shank, said hood section being defined by top, bottom, and side walls, said side walls 15 extending forwardly beyond the hood section proper, and a supporting wear plate member for the coupler shank, said wear plate member having the inner end section thereof confined between the bottom wall of the hood and the bottom edges of said extended side 20 walls and extending forwardly in supporting relation to the coupler shank to a point closely adjacent the head of the coupler.

11. In a railway draft rigging having draft 25 sills and a coupler, the combination with a carry iron supported at the outer ends of the sills; of yoke-acting means to which the coupler is operatively attached; means disposed inwardly of the carry iron arranged to slidably support said yoke-acting means and permit longitudinal movement of the latter; and a separate supporting plate for the shank of the coupler, said plate being extended both outwardly and inwardly of the carry iron and 30 slidable with respect to the latter, the inner end of said plate being detachably engaged with and supported by said yoke-acting means.

12. In a railway draft rigging having draft 35 sills and a coupler, the combination with a carry iron at the outer ends of the sills; of yoke-acting means to which the coupler is operatively connected; means for slidably supporting the yoke-acting means inwardly of the carry iron; a supporting member for the shank of the coupler interposed between the latter and the carry iron, the inner end of said member being detachably engaged with and supported by the yoke-acting means; 40 and cooperating means on said member and carry iron for limiting outward movement of the supporting member with respect to the carry iron.

13. In a railway draft rigging having draft 45 sills and a coupler, the combination with a carry iron at the outer ends of the sills; of yoke-acting means operatively connected with the coupler; supporting means inwardly of the carry iron for slidably supporting the yoke-acting means and permitting longi-

tudinal movement of the latter; a supporting plate for the shank of the coupler interposed between the same and the carry iron, the inner end of the plate being detachably connected by and supported by the yoke-acting means; means for limiting outward movement of said plate in a draft action; and cooperating means on the plate and yoke-acting means for limiting outward movement of the former with respect to the plate in a 70 draft action.

14. In a railway draft rigging having draft sills and a coupler, the combination with a carry iron at the outer ends of the sills; of a hooded yoke into which the coupler shank 80 extends and is operatively connected; supporting means inwardly of the carry iron for slidably supporting the yoke for longitudinal movement; and a plate interposed between the shank of the coupler and the carry iron, said plate being extended both outwardly and inwardly of the carry iron and slideable with respect to the latter, the inner end of said plate being detachably engaged with and supported by the hood portion of the 90 yoke.

15. In a railway draft rigging, the combination with an underframe structure; of a shock absorbing mechanism; a coupler; yoke means connecting the coupler and the shock absorbing mechanism; a carry iron at the outer end of the underframe structure; a follower interposed between the inner end of the coupler and the shock absorbing mechanism and directly engaged by the coupler during a buffing stroke; and a supporting slide separate from the yoke-acting means movably supported on the carry iron and interposed between the latter and the underside of the coupler shank and normally projecting outwardly beyond the carry iron to provide an extended support for the coupler shank, said supporting slide being engaged and moved outwardly by the follower during 100 releasing action of the mechanism.

In witness that I claim the foregoing I have hereunto subscribed my name this 8th day of March 1928.

ERNEST R. SCHULZ.
